[57] CLAIM

The ornamental design for a computer housing, as shown and described.

DESCRIPTION

FIG. 1 is a top front and right side perspective view of a computer housing showing our new design; FIG. 2 is a top plan view thereof; FIG. 3 is a front elevational view thereof; FIG. 4 is a left side elevational view thereof; FIG. 5 is a bottom plan view thereof; and, FIG. 6 is a back elevational view thereof.

The perforations are partially shown in the figures for ease of illustration and they are understood to continue across each of the indicated surfaces.

FIG. 1

FIG. 2

FIG. 3

FIG. 4

FIG. 5

FIG. 6
